EARRING HOLDER

Victor De Felice, Leominster, Mass., assignor to
Kaskadusa Tool Company, Inc., Leominster,
Mass., a corporation of Massachusetts

Application November 30, 1949, Serial No. 6,343

Term of patent 3½ years

(Cl. D80—9)

To all whom it may concern:

Be it known that I, Victor De Felice, a citizen of the United States, residing at Leominster, in the county of Worcester and Commonwealth of Massachusetts, have invented a new, original, and ornamental Design for an Earring Holder, of which the following is a specification, reference being had to the accompanying drawing, forming part thereof, in which:

Fig. 1 is a view in perspective of an earring holder, showing my new design.

Fig. 2 is a view in front elevation of the holder shown in Fig. 1.

Fig. 3 is a view in side elevation of the holder shown in Fig. 1.

I claim:

The ornamental design for an earring holder, substantially as shown.

VICTOR DE FELICE.
